UNITED STATES PATENT OFFICE.

ANDERS EDWARD ADOLFSSON, OF KORSNAS, SWEDEN.

APPARATUS FOR LIFTING AND TAPPING BUTTS.

Application filed September 15, 1924, Serial No. 737,902, and in Sweden April 6, 1921.

The most usual way of tapping butts consists in that the butt is first placed in an upright position so that a hole may be bored in the bottom for the cock. After the cock 5 has been inserted, the butt is placed aside and, for instance, rolled up or lifted onto a frame, whereupon air holes must be bored before the tapping can take place. It is impossible for a single person to manage a 10 butt of about 250 kilograms in this way, but two persons will be required at least for this purpose. If the butt contains heavy liquid, such as heavy lubricating oil, tar, syrup or the like, it will take quite some time, especially 15 in cold weather, after all work, to get something out of the butt. Besides, it is impossible entirely to empty the butt in this way.

With the device constituting the object of the present invention all these disadvantages 20 are eliminated. The butt may thus easily be managed by a single person. The bottom of the butt need not be bored into pieces and the tapping may be effected through the bung hole which on account of its being wider than 25 the opening of a cock will permit the contents of the butt to pass freely through the same, which contents for that reason may be entirely withdrawn from the butt.

The device according to the present invention 30 is substantially arranged in such a way that it does not only carry the butt suspended horizontally or nearly horizontally, but also makes it possible to rotate or to turn the butt thus suspended, for the purpose of tapping the contents of the butt through the bung.

A suitable embodiment of the invention involves the arrangement of endless ropes, 35 chains, bands or the like as supporting members for the butt, such ropes, chains, bands or the like being extended over rotatable pulleys, rollers or the like, embracing the butt and imparting a rotary action thereupon when the said pulleys, rollers or the like are rotated.

The annexed drawing shows an embodiment 45 of the invention. Fig. 1 shows the means for lifting and tapping butts, viewed in the longitudinal direction of the butt, and Fig. 2 shows the same device, viewed from 50 the side of the butt.

The means for lifting and tapping the butts or the "butt-turner" consists of a base *a* to which two uprights *b* of any suitable construction are secured, if only they are able to 55 bear the axle *c* and its load. The axle *c* runs in bearings *e*, and is provided with two fixed

cord pulleys *d*, as well as with a crank *f*. The bearings *e* are adapted to be turned about the pivot pins *g* which are mounted in the upper ends of the uprights *b*. These bearings are connected to each other by means of a lever *h* formed as a yoke or in some other suitable way, provided the bearings *e* are connected to each other. With regard to the pins *g*, the bearings *e* and the lever *h* consist of two double-armed levers acting simultaneously when the butt is lifted or lowered. The lever system described may be replaced by eccentric disks arranged on the bearings *e*, the said eccentrics being mounted pivotally in the same manner as the pins *g* in the upper ends of the uprights *b*. The bearings may also be connected with each other and formed into a pipe which latter is connected to a one-armed lever.

Closed bands *i* of suitable material run in the cord pulleys *d*, in which bands the butt is suspended.

The apparatus is used in the following way: The butt to be emptied—usually by 50 comparatively small quantities, according to the requirements as for instance in dispensing lubricating oils, syrup and the like—is rolled up onto the inclined plane *k* of the base, so that the butt will remain lying on 55 the top of the base. The lever *h* is then switched over—the movement being about 180°—whereby the cord pulleys *d* are lowered to an extent corresponding to the double distance between the center line of the pinions *g* and the axis of shaft *c*. The bands *i* are then slid over the ends of the butt, so 60 that these bands will occupy the position shown in the drawing. The lever *h* is then passed backwards and suitably locked. During the last-mentioned movement of the lever *h* the butt has been lifted and is now suspended in the bands. On turning the crank *f*, the butt may be turned as desired and in 65 such a way that the bung will be located on the upper side, in case the same was first directed downwards. Instead of the bung, 70 a pipe, conduit or nozzle is placed in the bung hole through which the contents of the butt are tapped. It will then only be required 75 slightly to turn the crank so that the butt will occupy the desired inclined position, and on the desired quantity having been tapped, the 80 crank is turned in the opposite direction, so that the tapping ceases. When, finally, the 85 butt contains so little, that tapping can take 90 place no longer in the manner above de-

- scribed, a vessel is placed under the butt, and the latter turned by turning the crank, until the bung hole will be directed right downwards, the butt being then entirely emptied.
- 5 The inclined plane, with the aid of which the butt is rolled up onto the base, may be advantageously constructed so as to be removable, which is of importance especially in cases where little space is at hand.
- 10 What I claim as new and desire to secure by Letters Patent of the United States of America is:—
- In an apparatus for tapping butts, the combination of two closed bands, block
- 15 sheaves supporting the bands, a shaft on which the sheaves are mounted, means for

rotating the shaft to rotate the sheaves, bearings for the shaft having supporting parts eccentric to the shaft, a base, an upright secured to one end of the base and provided with means for pivotally supporting the bearings by their supporting parts, a lever secured to the bearings for rotating the shaft whereby a butt resting in the bands can be raised or lowered to or from a position on the base and whereby a butt can be raised to a first position on the base to facilitate the assembly of the bands therewith and to be further moved by the chains and lever mechanism to a tapping position.

In testimony whereof I affix my signature.

ANDERS EDWARD ADOLFSSON.
